UNITED STATES PATENT OFFICE.

HENRY BURRMANN, OF DAVENPORT, IOWA.

SHOCK-ABSORBER.

1,372,934.

Specification of Letters Patent. Patented Mar. 29, 1921.

Application filed November 9, 1920. Serial No. 422,907.

To all whom it may concern:

Be it known that I, HENRY BURRMANN, a citizen of the United States of America, and a resident of Davenport, county of Scott, and State of Iowa, have invented certain new and useful Improvements in Shock-Absorbers, of which the following is a full and clear specification.

This invention relates to that type of shock absorbers adapted for connection to the free end of a leaf-spring to form a supplemental or auxiliary spring device to thereby assist the leaf-spring in cushioning the running of the vehicle, the preferred form of my device embodying also a snubber means to cushion or break the recoil, as more fully hereinafter set forth.

In the drawing—

Figure 1 is a view partly in section and partly in side elevation of the preferred form of my device;

Figs. 2 to 11, inclusive, are views of details hereinafter described, partly designated by reference characters;

Figs. 12 and 13 are detail views showing a modified form of the snubber;

Fig. 14 is a view of details of the swinging pressure-plates or bars which are used in both forms of my apparatus;

Figs. 15 to 20, inclusive, are views of a modified form of my apparatus partly illustrated in Figs. 12 and 13;

Fig. 21 is a detail view of the twisted or screw snubber-rod.

Referring to the drawings by reference numerals, 20 designates the usual leaf-spring whose free end is connected by a pair of links 21 to the lower ends of a pair of pressure-levers 22, each of said levers being provided with an integral ear 23 about midway its length, these ears being pivotally mounted on a horizontal bolt 24 carried by a bracket 25, this bracket being adapted to be rigidly affixed to a suitable part of the vehicle, it being shown in Figs. 1 and 16 as being adapted to be fastened to the brake-drum of the rear axle of a Ford type of motor vehicle, and in Figs. 15, 7, 8 and 9 as adapted for attachment to the front axle of the same type of vehicle.

Pivotedly mounted on a horizontal bolt 26 carried by the upper ends of the pressure-levers 22 is a cap 27, the connection to said bolt being by means of ears 28, and the cap being provided on its face opposite said ears with an annular boss 29. Affixed in the outer

ends of a pair of arms 30, formed integral with the bracket 25, is another horizontal bolt 31, which is pivotally mounted on another cap 32 which is a companion to cap 27. Between these two caps is arranged a coil-spring 33 whose normal tendency is to expand, thus tending to press the caps apart. The positions of the pivot-bolts 26 and 31 are such that the spring 33 has its axis inclined upwardly and away from the leaf-spring 20, to thereby favorably position the spring for compression by the load of the vehicle, the strain of the load being transmitted through the shackle-links 21 and the pressure-levers 22 and the top cap 29, the lever 22 being inclined outwardly and upwardly to thereby transmit pressure directly and centrally to the spring 33, both caps 27 and 32 and the pressure-levers 22 being pivotally mounted on horizontal axes to enable these parts to readily adjust themselves so as to at all times maintain pressure on the spring centrally thereof, it being obvious that this construction permits the spring 33 to bodily shift its angular position with varying load pressures.

To cushion and break up the recoil, I provide a snubber device. The preferred form of this device is shown in Fig. 1. In this form of the device I rotatively mount centrally in the cap 27 a rod 34, this rod being held to the cap by means of a locked nut 35 affixed to the outer end of the rod, the rod being shouldered to abut against the inner face of the boss 29. This rod depends centrally into the spring 33 and at its lower end it has rigidly attached to it a cap 36. This rod passes through another cap 37 which is a companion to cap 36 in that between these two caps there is confined a coil-spring 38 whose tendency is to expand in opposition to the main-spring 33. The cap 37 is formed integral with a pair of plates 39 whose lower ends are cast integral with the lower main cap 32, thereby constituting said cap 37 a rigid abutment for spring 38, which abutment will, of course, swing with the lower cap 32 under the varying conditions of the load. The stem 34 is desirably square in cross-section and is twisted to virtually convert it into a screw. This spiral portion of the rod passes through a hole in the center of the cap 37, this hole being square in cross-section but having its four inner walls slightly spiraled to conform to the four spiral faces of the rod.

The action of the snubber above described will be apparent. Upon compression of the main spring 33 under a load or a jounce, the spiral-faced rod 34 will rotate or partially 5 rotate as it is forced down through the rigidly-supported cap 37. This action will not subject the small coil-spring 38 to a torsional action, as the end-coils of this spring have a sliding action on the inner 10 faces of the caps 37 and 36. This downward movement of the cap 36, however, will permit the snubber-spring 38 to expand, as shown in Fig. 2. Then, upon recoil—that is, when the main spring expands upon release 15 of the load pressure—the snubber-spring 38 will be again compressed and the rod 34 will be given a reverse rotation. This recompression of the snubber-spring 38 and the friction caused by the quick rotation of the rod 20 34 will gently and smoothly overcome the destructive effects of the rebound.

In Figs. 1, 10 and 11, it will be seen that the bracket 25 is provided with a main depending plate having a bolt-hole 40 for bolt- 25 ing it to the brake-drum, while in Figs. 7 and 8 this bracket is formed of two depending hooks 41 adapted to engage under the flanges of the axle, these depending hooks being detachably held to the axle by means 30 of a goose-neck bolt 42 rigidly affixed to the axle and having its upper end provided with a horizontal tubular eye 43 which fits between the hooks 41 and is secured thereto by a bolt 44.

35 The snubber device illustrated in Figs. 12, 13 and 15 to 20, inclusive, performs substantially the same function as that which has been heretofore described. It consists of a pair of long flat bars 45 hinged together 40 at their lower ends on bolt 31 and extending entirely through the main coil-spring and emerging at the top thereof, the top-cap 27 being provided with a square hole to permit the upper ends of these members 45 to thus 45 extend beyond the spring. These flat members 45 are pressed apart at their upper ends by coil-spring 46 mounted upon a pin 47 extending through holes in the upper ends of said bars 45. The outer faces of 50 the bars 45 are serrated at 48, these serrations being preferably wave-like or rounded in formation, and at a point above the series of corrugations these members are provided with downwardly-facing shoulders 49 which 55 normally (that is, when the vehicle is without appreciable load) rest upon rollers 50 journaled between ears formed on the upper face of cap 27.

60 It will be observed that with this form of snubber the spring 46 acts in the same manner as spring 38 in the other form. The corrugations 48 together with the rollers 50 serve to destroy unpleasant noises as well as to reduce the wear of the parts and also 65 increase smoothness of operation.

The nature and scope of the invention having been thus indicated and its preferred embodiment having been specifically described, what is claimed as new is:

1. In combination with a leaf-spring, a 70 bracket having a pair of laterally-projecting arms, a pivot-bolt carried at the outer ends of these arms, a pair of pressure-levers pivotally connected at their lower ends to said leaf-spring and midway their ends to said bracket, 75 the levers being arranged outside of said arms and having guiding contact therewith, the upper ends of said levers extending above said arms, a cap pivotally hung on the upper ends of said levers, a companion cap pivotally mounted on the outer ends of said arms, and a compression spring arranged between 80 said caps, substantially as set forth.

2. In an auxiliary spring for vehicles, a 85 pair of rocking levers pivotally connected at their lower ends to the vehicle leaf-spring and inclining upwardly and away from said leaf-spring, these levers being pivotally supported at a point between their ends, a cap pivotally swung between the upper ends 90 of said levers, a companion cap and means for pivotally supporting it at a point near to said leaf-spring, and a compression spring arranged between said caps, for the 95 purposes set forth.

3. An auxiliary spring for vehicles comprising a main coil-spring, a pair of caps between which the spring is confined, means for compressing the spring under load pressures, and a snubber device inclosed within 100 the spring consisting of a rod rotatively mounted in the upper cap and having spiral faces, a snubber cap affixed to the lower end of this rod, another snubber cap through 105 which said rod passes, this snubber cap being fixedly carried by one of the caps of the main spring, and a snubber-spring maintained at a normal compression between said snubber-caps.

4. An auxiliary spring for vehicles comprising a main coil-spring, a pair of caps between which the spring is confined, means for compressing the spring under load pressures consisting of a rod carried by one of the caps and having a snubber-cap affixed 110 to its inner end, another snubber-cap affixed to the other main cap, and a coil-spring maintained under compression in opposition to the main spring.

5. A bracket or support for an auxiliary 120 spring of the type set forth consisting of a pair of arms having a pair of depending hooks adapted to engage the flange of the axle, and a bolt bolted to the axle and having a goose-neck portion extending up between said hooks and bolted thereto.

In testimony whereof I hereunto affix my signature.

HENRY BURRMANN.
